UNITED STATES PATENT OFFICE

2,503,345

CLOTHESLINE LAUNDRY PROTECTOR

John Masleck, Transcona, Manitoba, Canada

Application August 2, 1947, Serial No. 765,784

1 Claim. (Cl. 211—119.18)

1

My invention relates to a clothesline laundry protector, an object of the invention being to provide a device of the character herewithin described which is intended to lie upon the clothesline, and thus protect laundry hung thereon from being stained or in any undesirable way marked by dirt, or corrosion for example which may be clinging to the clothesline.

A further object of the invention is to provide a device of the character herewithin described which is in the form of a reel of longitudinally counter-folded tape preferably secured to a conventional clothesline pulley and bracket combination and housed within a surrounding enclosure or casing, but otherwise secured to a wall or other suitable support adjacent one end of the clothesline.

A further object of my invention is to provide a device of the character herewithin described, which, in a modification of the tape per se is longitudinally stitched adjacent the line of fold to preserve the tape as permanently folded.

A further object of my invention is to provide a device of the character herewithin described wherein the external ends of the tape may be clipped to an endless clothesline for frictional engagement therewith so that as the line is moved, the reel of tape will be unwound and automatically lie on the line as it emerges, the reel being preferably attached to and projecting from the associated conventional clothesline pulley and bracket combination with a pulley secured to the armature of the reel so that the tape will be rewound upon movement of the line in the opposite direction all for the purpose of eliminating the necessity for a separate operation of pulling out the tape and re-winding it as by means of a handle in substitution of the pulley herewithin described.

A further object of my invention is to provide a device of the character herewithin described which is of conspicuously simplified construction, simple to operate, inexpensive, and which will give long service without attention.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings, in which—

Figure 1 is a perspective representation of my clothesline laundry protector in situ and in combination with a conventional clothesline pulley

2

and bracket combination or secured to a supporting wall.

Figure 2 is a side elevation shown partly fragmented of my reel enclosure or housing.

Figure 3 is a fragmentary perspective representation of my longitudinally counter-folded and stitched tape.

In the drawings like characters of reference indicate corresponding parts in the different figures.

It is well known that considerable annoyance is caused to housewives and others by the discovery of dirt, stains and the like upon laundry which has been hung upon clotheslines, particularly in industrial areas where smoke settles upon the line. In the case of metallic lines also, oxidation is responsible for considerable staining.

Accordingly, I have devised a unit for attachment adjacent one end of a clothesline as illustrated in the accompanying Figure 1, whereby the line may be protected efficiently and conveniently as clothes are placed thereupon, in such a way that the clothes and other laundry will not be in contact with the line.

My invention accordingly consists of an enclosure, which as illustrated takes the form of a housing 1 of substantially semi-circular shape, and having a pair of parallel side walls 2, the device being mounted by means of a pair of brackets 3 secured to and projecting horizontally from the vertical yoke 4 of a conventional clothesline pulley and bracket combination collectively designated 5. Adjacent and positioned externally of one side of the housing 1 is a reel operating pulley 6 to which is keyed an armature 7 spanning the side walls 2 and being journaled therein. This armature is diametrically slotted as at 8 to receive the inner end of a reel 9 of laundry protecting tape 10.

The tape 10 is wound upon the armature 5 in a longitudinally counter-folded state as is best illustrated in the accompanying Figure 3 and is intended to emerge through a transverse slot 11 in housing 1. The tape is preferably longitudinally stitched as at 12, that is, adjacent the line of fold 13 to assist in the permanent preservation of the said fold. By reference to Figure 1 it will also be noted that the external end 14 of the tape has secured thereto a spring clip 15 whereby the same may be frictionally secured at any point upon the length of the under-run 16 of an endless laundry line 17.

The under-run 16 of the laundry line 17 passes over the pulley 6, and from the foregoing it will be apparent that laundry may be conveniently

pegged upon the clothesline adjacent the end thereof which is illustrated in the accompanying Figure 1 at the same time as the tape 10 is automatically played out with movement of the line in view of the external end thereof being clipped thereto as aforesaid.

Conversely as the dry clothes are unpegged and detached from the under-run 16 adjacent the end of the clothes line illustrated in Figure 1, and the said under-run moves in the direction of arrow 18, it will be apparent that the tape 10 will be wound on to the reel 9 due to rotation of pulley 6 and armature 7 under the influence of the frictional contact of the line with the pulley as clearly depicted.

From the foregoing, it will be recognized that I have provided a conspicuously simple means for preserving laundry against the possibility of soiling, staining and the like, without any inconvenience to the operator, and since various modifications can be made in my invention as hereinabove described and many apparently widely different embodiments of same made with the spirit and scope of the claim without departing from such spirit and scope, it is intended that all matters contained in the accompanying specification shall be interpreted as illustrative only and not in a limiting sense and I desire only such limitations placed thereon as are specifically expressed in the accompanying claim.

What I claim as my invention is:

The combination with a conventional clothes-

line pulley and supporting bracket consisting of a vertically disposed, diametrically encircling yoke and right angularly related attaching clevis, together with an endless clothesline, having upper and lower runs, of a reel housing, a reel of longitudinally counterfolded tape therewith intended to lie upon the clothesline to protect laundry hung thereon against dirt, stains and the like, an armature connected to said reel and rotatably mounted in the housing, a pulley fixed to said armature and frictionally engageable with the lower-run of said clothesline, a pair of brackets projecting from said yoke and supporting said housing, and means for attaching the end of said tape to said clothesline for unwinding said reel during the movement of said clothesline around said pulley.

JOHN MASLECK.
